METHOD OF AND APPARATUS FOR
AIRPLANES

William M. Fellers, Washington, D. C.

Application September 30, 1929
Serial No. 396,843

10 Claims. (Cl. 244—2)

(Granted under the Act of March 3, 1883, as
amended April 30, 1928; 370 O. G. 757)

This invention relates to an improved method of and apparatus for airplanes, and more particularly to their preparation for flight, and still more particularly to the regular or occasional such preparation of large numbers of aircraft more especially where space is limited and such craft and personnel are required to be handled, conserved and accommodated efficiently, economically and speedily without impairing visibility, comfort and health of personnel, or the safety of such craft and their operatives.

Heretofore, airplanes have been taken from their hangars to any convenient indefinite place, there secured and their motors started and warmed up to the requisite extent before flight. Each usual propeller of such craft exerts a force upon the air of substantially five pounds per horse power of the motor.

I have found that such force causes a column of air to be thrown backward and downward, which column strikes the earth with great violence, and causes a substantial amount of dust to be thrown up which is increased substantially by erosion of the earth due to said force; that said dust from one or more planes tends to substantially lower visibility and increase liability to accident, settles on and is liable to be taken into the motors with the intake-air and thereby and otherwise damage such motors and planes, besides being inconvenient and liable to be harmful to personnel; that said erosion causes holes to be formed in the earth's surface which must be frequently resurfaced; and that said conditions have required stronger anchoring of planes being warmed up, more extensive areas of the flying field which cannot be used for other kindred purposes, widely scattered hangars or long trips of planes and personnel to and from the hangars, a larger force of employees on such flying fields, and more extensive investments in land for such fields which land is usually of great value being usually in or convenient to large cities.

The object of my present invention is to substantially overcome said conditions, difficulties and liabilities by providing an improved method of and apparatus for airplanes whereby the heretofore capacity of a flying field for handling planes in and out may be increased manyfold without the harmful conditions, liabilities and increased operating cost and investment heretofore indicated and with other advantages herein-after rendered more apparent.

To attain these and other objects, and in accordance with the general features of this unitary invention of related and interdependent com-

ponents, my improved method contemplates and includes the association of the several hangar volumes as close together as the anti-fire spreading characteristics of the walls may admit to check the spread of fire from one to another; the association therewith and adjacent thereto of a definite and certain warming-up area preferably intermediate the hangar area or areas and the take-off area of the flying field; and

Further contemplates the association in said warming-up area of airplanes which association may be safe as close together in each horizontal direction as ready ingress and egress may conveniently admit, and that airplanes may be anchored in said association with anchors no more than, if as much as, heretofore employed; and

Further contemplates and includes, in said warming-up area, leading the air-exhaust and other contents of each or any propeller blast away from the volume occupied, or adapted to be occupied, by adjacent plane or planes which may otherwise be affected thereby; and more specifically contemplates that the direction of said leading may preferably be upward; and more specifically contemplates the association of conveying areas in said warming-up area, and that said conveying areas be associated with the tails of airplanes to be anchored in said warming-up area, and that the preferred association of planes and conveying areas may be the association of planes tail towards tail with a conveying area or areas intermediate such tails; and still more specifically contemplates that said leading and conveying in said conveying areas may be by deflection content of the content of each or any propeller blast away from contact with erosive earth and away from volumes occupied, or adapted to be occupied, by other planes; and still more specifically contemplates that said leading or deflection in said conveying areas may be in substantially definite paths which may be fixed or varied;

And further contemplates and includes, as a step thereof, the association of a taxiing area with said warming-up area, and that said taxiing area be preferably intermediate said warming-up area and the flying field with said taxiing area extending into said field at any convenient location; and

Further contemplates and includes the taxiing of warmed-up planes from said warming-up area over said taxiing area and into the flying field; and

Further contemplates and includes the step of associating with the surface of said warming up, conveying and taxiing areas a deflecting and re-

sisting medium whereby the violence of the propeller blasts upon said medium will not erode the same and the many taxyings of planes thereover will not mar the smooth surface thereof, and upon which medium taxying planes exert less force proportionate to their speed and their weight that is counterpoised by the air and whereby the taxying planes are precluded from rutting the surface of the flying field juxtaposed to said extension of the taxying area and greater area afforded said juxtaposed areas to further minimize rutting; and

Further contemplates the association in the warming-up area of planes some facing the taxying and flying areas and some at an angle to said areas, or either of said areas, and that passage areas be associated in said warming-up area with and between rows of planes, or rows adapted for planes, being or to be warmed up; and that the planes warmed up be led from its specific portion of the warming-up area through the passage area or areas to the taxying area; and that the planes at an angle to the taxying and flying areas, or either of them, may be associated with their tails toward each other and in rows, with the conveying area or areas intermediate said tails; and further contemplates other steps as may more fully appear in the following detailed description, drawings and the appended claims.

To demonstrate the practical utility of my said method a related, improved and novel apparatus is provided embodying my invention, and which may be used very advantageously and economically in practicing my improved method as a unitary invention. Such apparatus also serves as an example, to those skilled in the art, of the facility with which, after becoming familiar with my invention, the many forms and kinds of existing apparatus, with or without substantial modification, may be employed in the efficient practice of my said method.

Said provided apparatus contemplates and includes the construction of the several necessary hangars as close together as the fire-spreading characteristics of the materials forming their walls and roofs may admit for safety from fire spread; and preferably in convenient association therewith is constructed a field wherein planes may be warmed up and tested in preparation for flight as well as tested after flight before being placed in their respective hangars, said warming-up field being preferably intermediate the hangars and the take-off portion of the flying field.

Said provided apparatus further contemplates the provision of means on said warming-up field for leading the air, exhaust and other content of preferably each propeller blast away from other planes which otherwise may be affected thereby; and more specifically contemplates that said means preferably lead said propeller blast content upwards, and that said means may constitute conveyors; and still more specifically contemplates that said means may be formed of deflectors which receive and deflect to harmless points the content of propeller blasts, and that said means may be fixed or varied relative to the warming-up field, and that when said means is fixed the planes are properly associated therewith, and that when said means may be varied it may be properly associated with each plane to be served thereby; and

75 Said provided apparatus further contemplates

the taking additional advantage of said means, conveyors or deflectors, in which the planes in the warming-up field may with safety be associated as close together in each horizontal direction as convenient egress and ingress may admit, and there held by anchors subject to no more, if as much, stress as heretofore required in warming up or testing planes such distances apart as to be unaffected by each other's normal propeller blasts; and still further contemplates the taking of further unexpected advantage of said means and attaining substantial economy of valuable space by combining said means and its planes served thereby in row with the tails of said plane towards said means, and preferably with said planes facing toward the flying field, and for the attainment of greater economy in valuable space it is contemplated that there be combined with said means double rows for the accommodation of planes with said means intermediate each such double row and the tails of the planes therein extending toward each other and said means, with a passageway intermediate each such double row for the ingress and egress of planes to and from each side of said rows, and with the planes in said double rows facing at an angle to the flying field, and with gaps in said first stated row or rows for the passage therethrough of planes to and from their respective hangars, and that said passageway or ways and said gap or gaps be respectively substantially in alignment preferably; and

Said provided apparatus further contemplates the construction of a taxying field preferably intermediate the warming-up and flying fields; and more specifically contemplates the substantial extension into the flying field of said taxying field preferably at a point which is more preferably at about the center of one side of the taxying field, and that still more preferably said extension be progressive throughout a substantial part of the juxtaposed portions of said fields; and

Further contemplates and includes the providing of means whereby the violence of the possibly numerous propeller blasts, each likely to recur at substantially the same spot, will not erode and tear substantial holes in the warming-up field, and will not throw up great clouds of or any substantial dust which are liable to cause lowered visibility and serious accident and be intaken with the air into their motors and thereby and otherwise damage the motors and be inconvenient and harmful to personnel; said means preferably including the hard surfacing or concreting of the warming-up and taxying fields, which incidentally will also avoid their being rutted by the wheels of the planes passing thereover, and which surfacing is merged into and/or associated with the deflecting surface of the conveyors.

Other constituent features, provisions, forms, substantial economies and advantages of my said provided apparatus, as well as the foregoing and other objects of my invention, will be rendered more apparent from the following detailed description and accompanying drawings, illustrating one embodiment, with some optional details, of my improved apparatus, of the many different forms and characters of apparatus each of which may be readily adapted by association or otherwise for employment in the practice of my improved method.

In the accompanying drawings, illustrating my invention in its apparatus aspect, and in which

like characters of reference indicate the same parts.

Figure 1 is a plan view with portions broken away;

5 Figure 2 is a sectional elevation view on line 2-2 of Fig. 1;

Figure 3 is an enlarged sectional elevation view of a part of my invention;

10 Figure 4 illustrates a detail of construction; and

15 Figure 5 is a perspective view illustrating a modified detail of construction.

In the drawings, 10 represents the flying field of any desired size and configuration or area; 11 represents a taxiing field; 12 represents a warming-up field; 13 represents hangars of which there may be constructed any desirable number to accommodate the requisite number of planes; 14 represents a roadway leading from each hangar 13 to the warming-up field 12.

20 Upon field 12 is provided means 15 for leading or conveying the blasts of the various propellers of airplanes liable to be thereon away from interference with adjacent planes. Said means 15 enables planes to be placed as close together in all horizontal directions as convenient ingress and egress may admit and without requiring any more, if as much, stress upon the anchoring of each plane than was required where the planes were scattered widely in warming up. Said means 15, which makes such safe, orderly and economical congestion possible, also requires the hard surfacing or concreting 16 of the top surface of the whole of fields 11 and 12, which I have provided, combined and associated with said means 15, in order to preclude the possibility of the great force of the many possible propeller blasts, each of which is likely to recur repeatedly substantially at the same place, eroding and digging substantial holes in the surface of field 12, and to a lesser extent in field 11, and thereby and otherwise raising huge clouds of dust which greatly lowers visibility and greatly increases the liability to accident as well as inconveniencing and being harmful to personnel, and which dust would be liable to get into the motors through the intake air and injure them. Said hard surfacing 16 further decreases the tendency of fields 11 and 12 to rut by the frequent action of the landing wheels of planes thereon.

50 In the instance shown in Figure 1, there are a plurality of rows of means 15 facing in different directions, one of which directions being facing the fields 10 and 11, and the other rows facing at an angle or angles thereto. One of the rows of means facing fields 10 and 11 preferably extends across the fronts of and between the several hangars 13 with gaps therein substantially coincident with the roadways 14 leading into the hangars 13. The rows of means 15 facing at an angle or angles to fields 10 and 11, or either of them, preferably commence a convenient distance toward field 11 from said last described row 15 and extend a desirable distance toward field 11, with the rows 15 at the opposite ends of field 12 formed of single means 15, while the intermediate rows of means 15 are each formed of double means 15. Across the ends of the rows of means 15 extending towards field 11 is a row of means 15, in the instance shown in Figure 1, parallel with the row of means 15 extending across the hangar fronts. Along the sides of the rows of means 15 facing towards field 11, as well as along the adjacent sides of the intermediate rows of means 15, are adapted to be placed respectively rows of planes to be warmed up preparatory for

flight, or to be tested after flight and before being placed in their hangars, each plane with its tail extending toward its adjacent row of means 15. Each plane preferably extends at a right angle from its respective row of means 15 extending across the front of the hangars, and parallel therewith, so that such planes face the field 11, while planes along the intermediate rows of means 15 preferably face away from said means at an angle of about 90 degrees, although any desired angle may be employed.

80 Between the row of planes across the hangar fronts and the adjacent ends of the next forward rows of means 15 is a roadway 17 communicating with the roadways 14 through gaps formed in the row of planes and means 15 across the hangar fronts, and also communicating with roadways 18 intermediate each row of planes, or spaces adapted to receive planes, juxtaposed to the several rows of means 15 at substantially a right angle to the row of means 15 extending across the hangar fronts. Said roadways 18 each lead into field 11 through gaps in the row of means 15 juxtaposed to the front ends of the rows of means 15 flanking the roadways 18.

90 In Figures 2 and 3 I have shown the means 15 formed integral with the hard surfacing or concrete composing the top surface 16 of fields 11 and 12, and as consisting of a concave surface 19 extending from flush with the top surface 16 upward to the desired height where the same may terminate in a point, but I prefer to have the same terminate in a convex curved surface 20. The propeller blast strikes the top surface 16 preferably at or near its junction with the curved surface 19 which deflects said blast upward and away from the tail of the plane whose propeller or propellers produced said blast until said blast comes in contact with the oppositely curved surface 20 which is also conductive to the continued upward deflection of the blast as well as to permit the expansion and diffusion of said blast and further gives a pleasing appearance to the top of each projection forming said means 15. Where the means 15 is desired to be formed in double rows, back to back, as shown in Figures 1 and 2, the curved tops 20 are conveniently joined together and the double means 15 formed of a single projection integral with the top surface 16 of field 12.

95 In Figure 4 I have shown the means 15, there-in designated as 15a, detachable from and not formed integral with the top surface 16 of field 12, and as being formed of an ogee curved plate 21 extending from top surface 16 to the desired height with its lower edge provided with a series of holes to receive lag bolts 22 removably screwed into conical members 23 set or molded into and flush with the top of the concrete surface 16. When the means 15a is desired to be formed in a double row, plates 21 are set back to back with their edges adjoining. The shape of said plates 21 enable them to be nested together in great numbers in a small space when not desired to be used. The lag bolts 22 may be readily screwed into their respective members 23, each set or molded into the concrete top surface 16 of field 12 at predetermined points where means 15 are desired to accommodate more than the usual number of planes at times. The screw holes in members 23 being adapted to be filled, when not occupied by bolts 22, by wood or other plugs flush with the top surface of 16.

100 In Figure 5 is shown a portable type of means 15 which is designated 15b formed of a sheet 25

of metal having its front edge 26 adapted to touch the ground or the top surface 16, thence it gently slopes upward and backward to 27, thence it slopes gently backward and into a substantial upward curve 28 concave toward the front, and terminates at its top in a relatively small curve 29 with its convex surface toward the front. This sheet 25 is preferably relatively thin, and hence is reinforced by frame 30 spotwelded or riveted thereto, as is also an axle 31 having wheels 32 revolvably mounted upon opposite ends. This means 15b may be conveniently moved into position, or elsewhere when not in use, by raising its front end 26 off the ground and moving it about as readily as any two-wheeled hand truck. In use said means 15b is moved with its front end 26 to and under the tail of the plane it is desired to serve, and there secured by any convenient means. The width of sheet 25, either 10 in one or any required number of pieces secured together, is such as to receive the column of air set in motion by the propeller of the plane whose motor is being warmed up or tested. The air is received by said means 15b, which deflects the 15 same upward and away from possible interference with other planes and away from contact with dust forming surfaces.

The function of the means 15 will be described with reference to Figure 3 wherein a conventional airplane is shown in operative relation thereto with its usual anchorage omitted. When the motor is started for warming up or for testing, the propeller creates a rearward blast of high 20 turbulence and substantial force, which, but for my invention would produce the conditions with their harmful results heretofore stated. With 25 my invention these harmful results are eliminated and no additional harmful results are encountered. The substantial thrust of the propeller blast, 30 coming downwardly and rearwardly, is received by the hard surface 16 at and adjacent its junction with said curved deflecting surface 19, which readily deflects the same backward and upward in substantially a streamline. When said deflected 35 propeller blast reaches curve 20 it commences to expand over curve 20 and to diffuse into the atmosphere without liability to other planes, its motion being substantially upward.

When a plane has been warmed up sufficiently 40 for flight it is preferably manually attended and guided by ground attendants through either of both roadways 17, 18 and released to its pilot at the junction of roadway 18 and field 11, whereupon the pilot taxies the plane across the taxying 45 field 11 preferably in the direction from which the wind comes, and at accelerating velocity. When such plane reaches the junction of the hard surface 16 of field 11 with the soil of flying field 10 the action of the air upon the 50 plane wings has counterpoised the whole, or a substantial part, of the weight of the plane from the wheels, which obviates or greatly reduces the rutting of field 10. This anti-rutting is also substantially contributed to by the progressive extension of the hard surfaced taxying field into the flying field, preferably by substantial outward curves which afford greatly increased area to the junction between fields 10 and 11 and thus further decrease the liability of said rutting; 55 while the uniformly smooth surface of taxying field 11 afforded by its hard or concrete surface 16 enables the taxying of the planes thereover at substantially higher accelerated velocities with safety and comfort, and which further lessens said liability to rutting because such velocities

transfer in lesser time more of the weight of the planes from their wheels to the air.

It will be readily understood by those skilled in the art that the foregoing description of means 15 associated with Figure 3 is also applicable to 80 the substantially like means illustrated in Figures 4 and 5.

To avoid the placing of the tail skid 33 of an airplane upon the top of the front edge 26 of conveyer means 15b to prevent the force of the propeller blast from driving means 15b backward and away from the airplane, brace rods 34 are pivotally connected, one to each rear corner of means 15b. Rods 34 are preferably provided with sharp free ends and are adapted to extend downward and rearward from their respective pivot points and to receive all or a part of the weight of means 15b from its wheels 32 when set in position to receive and convey by deflection the blast from the propeller of its correlated 90 airplane.

Rods 34 are preferably universally pivoted to means 15b, and a simple and convenient such pivot is shown in Figure 5 consisting of a ring 35 attached to the back edge of means 15b and 100 adapted to project back of, above and below said edge. Each ring 35 contains the loop 36 formed of the upper end of its respective rod 34. In bracing means 15b the upper end of loops 36 of rods 34 are adapted to engage the lower 105 crotch formed by means 15b at its point of attachment to rings 35, while when not employed in bracing said rods may be conveniently disposed along the top of the rear edge of means 15b with loops 36 occupying the upper such crotch.

My provided taxying area, with its smooth artificial covering or surface, I have discovered in the course of long experiments in launching and landing airplanes, dispenses with the necessity for an airplane launching catapult which is expensive, shortlived and cumbersome, in cases other than such as roofs and ship decks where usually space is inadequate for my very limited taxying area. Said area affords all of the safety and airplane velocity acceleration in a relatively 115 short airplane travel that its motor-propeller capacity permits. Said velocity acceleration throughout the extent of the taxying area is substantially greater than has heretofore been possible with airplanes under their own motive 120 power, and which usually takes the airplane off of the area, or causes the air to sustain most of its weight, before the smooth joint between said area and flying field is reached. Hence, and also by reason of the great length of said joint 130 with the perimeter of the take-off end of said taxying area remains substantially unrutted notwithstanding the far greater capacity and use to which airports provided with my invention are subjected. Without my invention an airport of far less capacity and use would be almost daily rendered unsafe and useless by rutting in extensive areas, or require almost constant expensive repairing, besides having the other stated substantial difficulties and dangers which my 140 invention also obviates readily and inexpensively.

In landing airplanes upon airports provided with my invention it may also be advantageous, when desired, that such planes first make landing contact upon the take-off end of the taxying area, or adjacent thereto, when the air is usually sustaining most of the weight, whereby the liability is substantially obviated of rutting the portion of the flying field smoothly juxtaposed to the extensive perimeter of the take-off 150

- end of the taxiing area. My said taxiing area also enables such landing planes to be stopped by their brakes, or other stopping means, in substantially shorter space than has heretofore been possible with uniform safety, which safety is substantially contributed to by the increased confidence of pilots in the uniform characteristics for substantially safer and quicker take-offs and landings of airports equipped with my invention.
- 10 Those skilled in the art will appreciate that this invention affords manyfold the normal capacity of an airport for handling airplanes in and out, and thereby greatly conserves space and its great cost and upkeep with practical safety substantially increased and the avoidance of dangerous ruts and dust and the injuries and delays occasioned thereby, with the preservation of the prevailing visibility, even during the use of an airport to the maximum capacity rendered possible by my invention.
- 15 With my invention understood, those skilled in the art and exercising the skill of their calling may readily adapt it in either or both of its method and apparatus aspects to various conditions and in ways and forms more or less widely different from the illustrating form shown in the drawings, with or without substantial modification and within the scope and spirit of my invention and its appended claims.
- 20 Retrospectively considered, and working after the fact when everything seems so natural and obvious, the extremely simple and relatively inexpensive method and means for its practice which I have devised may mislead those unskilled in the art to regard the same and its steps and elements as being each of minor, if any, advance in the art; but those skilled in the art will appreciate, and the facts are, that such simplicity and inexpensiveness were attained by and through long, arduous and expensive experiments in the launching and landing of airplanes, including catapults and artificial landing means, and successive improvements and developments of my contributing accomplishments, and that each step or feature of my method and means substantially contributes to the attainment of greater safety of persons and property and the conservation of liability, expense and investment so essential to the dissemination of danger and aviation and the more universal adoption of aviation.
- 25 The herein described invention may be manufactured and used by or for the Government of the United States for governmental purposes without the payment to me of any royalty thereon or therefor.
- 30 Having now so fully described my invention that others may therefrom make and use the same, what I claim and desire to secure by Letters Patent is:
- 35 1. An airport for airplanes having a flying field, an area in which the motors of airplanes may be warmed up or tested while close together, a taxiing area intermediate said area and the flying field, and means for preventing the propeller blasts of airplanes from eroding the surface of said areas and for leading away from another airplane such blasts as may otherwise affect said other airplane.
- 40 2. An airport for airplanes having a flying
- 45 field, an area or areas in which airplanes may be placed so close together that the propeller blast of one airplane may affect another airplane, a taxiing area intermediate said first named area or areas and the flying field, a communication area intermediate said first and second named areas, and means for preventing the propeller blasts of airplanes from eroding the surface of said areas and for leading away from another airplane such propeller blasts as may otherwise affect said other airplane.
- 50 3. In means for warming up the motors of airplanes while nested, a deflector rigidly mounted between two or more planes and having its opposite sides diverging downwardly and adapted to receive and deflect from each other the blasts of the propellers of such planes.
- 55 4. In means for warming up the motors of airplanes while nested, a deflector formed of concrete or the like between two or more plane positions and having its opposite sides diverging downwardly and adapted to receive and deflect from each other the propeller blasts of such positioned planes.
- 60 5. In means for warming up the motors of airplanes while nested, a deflector plate adapted to receive and deflect from another plane or planes the propeller blast of an airplane, and means for removably mounting said plate, in its deflecting position.
- 65 6. In means for warming up the motors of airplanes while nested, a deflector plate extending downwardly and away from its upper edge and adapted to receive and deflect from another plane or planes the propeller blast of an airplane, and means including lag-bolts for removably mounting said plate in its deflecting position.
- 70 7. In means for warming up the motors of airplanes while nested, a deflector plate adapted to receive and deflect from another plane or planes the propeller blast of an airplane, and means for portably mounting said plate in different deflecting positions.
- 75 8. In means for warming up the motors of airplanes while nested, a deflector plate extending downwardly and away from its upper edge and adapted to receive and deflect from another plane or planes the propeller blast of an airplane, and wheels upon said plate for portably mounting said plate relative to the plane it is to serve.
- 80 9. In means for warming up the motors of airplanes while nested, a deflector plate adapted to receive and deflect from another plane or planes the propeller blast of an airplane, wheels upon said plate for portably mounting said plate relative to the plane it is to serve, and brace means for bracing said plate in its desirable deflecting position.
- 85 10. In means for warming up the motors of airplanes while nested, a deflector plate adapted to receive and deflect from another plane or planes the propeller blast from an airplane, means for portably mounting said plate relative to the plane it is to serve, brace means for bracing said plate in its deflecting position, and means for movably securing said brace means to said plate.

WILLIAM M. FELLERS.
